UNITED STATES PATENT OFFICE.

EMIL S. NEUZIL, OF CHICAGO, ILLINOIS.

GAME OR PUZZLE.

Application filed June 18, 1926. Serial No. 116,795.

This invention relates to a game or puzzle and more particularly to a contest involving the plays of a baseball game.

One of the objects of the present invention is to provide a game or puzzle which involves the different plays of a baseball game and in which any number of contestants may take part.

Another object of the invention is to provide a game or puzzle in which a score card is supplied to the contestants, who insert the proper plays in each inning on the score card.

A still further object of the invention is to provide an improved game or puzzle which involves the various plays in a baseball contest in which the plays are designated by certain combinations of symbols or letters, which symbols or letters may be placed opposite the word "Runs" are the totals of the number of runs made during each inning of the game.

These and other objects are accomplished in the manner hereinafter described and particularly pointed out in the appended claims.

Referring to the drawings:

Figure 1 shows one way in which the score card may be filled out to complete the nine innings of the game; and

Figure 2 is a guide in which the different plays of a baseball game are designated by certain combinations of two letters which include the letters *a* to *j*, inclusive, of the alphabet.

In illustrating one embodiment of my invention I have shown the same as comprising a score card which is shown in Figure 1 of the drawing, which consists preferably of a sheet of paper, a plurality of parallel ruled lines running horizontally on the sheet as shown at 10, and a plurality of transversely arranged lines as shown at 11, dividing the major portion of the sheet in nine squares transversely of the sheet. These squares are numbered from 1 to 9, inclusive, and are designated by the word "Innings" at the top left-hand corner of the sheet. Below the word "Innings" in the vertical column are a plurality of names indicating the players, such as Mostil CF, Scott SS, Collins 2B, Sheely 1B, Falk LF, etc. These names indicate the players, and the abbreviations following the names indicate the position the players occupy at a baseball game, such as center field, short stop, etc. At the bottom of the sheet the word "Runs" appears, and

opposite the word "Runs" are the totals of the number of runs made during each inning of the game.

The construction of the score card above described and illustrated in Figure 1 of the drawing is substantially like the score card or score sheet now used in connection with keeping score of a regular baseball game. But in playing my improved game or solving the puzzle I preferably block out certain squares as shown at 12 throughout the score card, leaving certain spaces as shown at 13 blank, which are to be filled in by those in the contest. In the blank spaces 13 each contestant inserts one combination of symbols or letters, which designates a certain play in a baseball game, as indicated by a guide which will hereinafter be described.

In Figure 1 of the drawing I have blocked out five squares in each of the innings 1, 4, 6, and 9, and four squares in each of the innings 2, 3, 7, and 8, as indicated at 12, but it will of course be understood that a lesser number of squares may be blocked out, in which case there will be a greater number of blank spaces to be filled in by the contestants; but when the game is being played or the puzzle solved each contestant is supplied with a score card having the identical number of squares blocked out, giving all the contestants an equal chance in filling in the blank squares.

The preferred rules of the contest in playing my improved game are as follows:

No letter from "a" to "j" is to be used more than once in scoring the plays for any one player; for example, if Mostil's first turn at bat makes the two base hit and the letters "ae" are inserted in the first square in the first inning, the contestant cannot use the letters "a" or "e" in scoring or filling in the first blank spaces under the innings 3, 5, 6, or 8. The same is true about the other players.

The second preferred rule in playing my improved game is that no combination of two letters representing a certain play in baseball can be repeated; for example, a contestant cannot use "ae" or "ac", or any other combination of two letters more than once throughout the entire score card.

In order to assist the contestants in supplying the proper combinations of letters to designate the proper plays in the blank spaces on the score card, I have provided a guide as shown in Figure 2 of the drawing,

which comprises combinations of two letters from "a" to "j" inclusive, as indicated at 14. For example, the letters "ab" indicate "flied out;" the letters "ac" indicate "sacrifice 5 hit;" the letters "ad" indicate "struck out;" the letters "ae" indicates "two base hit;" etc., with a different combination of letters representing the different plays.

In playing the game the object is to insert 10 the combination of letters in each of the blank spaces which will give the greatest number of runs and yet at the same time complete a perfect score card, and the contestant scoring the greatest number of runs 15 will be the winner of the contest.

For the purpose of illustrating one manner in which the blank spaces may be filled out in order to complete a perfect score card, I have shown that in scoring the runs 20 the contestant follows the play just the same as it would be followed in a real baseball game; for instance, the contestant may start off as indicated in the drawing, with Mostil making a "two base hit" by placing the letters 25 "ae" in front of his name in the first inning. The contestant can then "sacrifice" Mostil to third base by placing the letters "ac" in front of Scott's name, as indicated in the drawing. The contestant can then 30 score a run by placing the letters "cd" in front of Collins' name in the first inning, which will indicate Collins made a "sacrifice fly," scoring Mostil and making one run with two out. Then, in order to complete the 35 inning, Sheely, the last man to "bat" in the first inning, can close the inning by striking out, which would be indicated by the letters "ad." In a similar manner the contestant can fill in the other innings from 2 to 9, 40 inclusive, observing the rules above referred to until the score card is completely filled out, with each inning being completed by having three men out, as required in a regular baseball game.

45 It will be understood in connection with playing my improved game that a base runner may be advanced two bases on a "hit" designated as a single; and on a play designated as "grounded out" the contestant can advance the runner one base if it is the first or second "out" in the inning.

While in the above specification I have designated certain spaces to be left blank for the contestant to fill in, it will of course 55 be understood that the number of blank spaces in each inning may be increased or decreased in playing the game or solving the puzzle, but of course it is desirable when playing the game between one group of contestants to provide score cards with the 60 identical number of spaces left blank.

While in the above specification I have described one form which my invention may assume in practice, in which certain combination of letters represent certain plays it 65 will of course be understood that other symbols or combination of symbols may be used and other modifications made without departing from the spirit and scope of the invention, as expressed in the following 70 claims.

What I claim as my invention and desire to secure by Letters Patent is:

1. In a game or puzzle the combination of a score card having certain characters representing plays, a guide having certain combination of characters representing plays of a baseball game whereby only certain combination of characters in said guide representing certain plays may be inserted on said 80 score card for completing said score card.

2. In a game or puzzle comprising a score card having blank spaces thereon, a guide having combinations of letters representing certain plays in a baseball game, whereby 85 said combinations of letters may be inserted in the blank spaces on said score card for completing a perfect score card.

3. In a baseball game or puzzle comprising a score card having a plurality of players and divided off in square blanks forming different innings of the game, a guide comprising combinations of two letters of the alphabet from "a" to "j", inclusive, each combination of two letters indicating a certain play of a baseball game, whereby 95 said letters may be inserted in the blank spaces on said score card for completing a perfect score.

4. In a baseball game or puzzle comprising 100 a score card consisting of a plurality of players and a plurality of blank spaces opposite the names of said players, and a guide comprising a plurality of combinations of letters, each combination of letters designating a certain play in baseball, whereby the contestants may insert a combination of letters in the blank spaces on said score card for completing the perfect score card.

5. In a baseball game or puzzle comprising 105 a score card consisting of one team of nine players, each player having a plurality of blank spaces opposite his name and arranged in innings, a guide comprising a plurality of combinations of two letters of the 115 alphabet, from "a" to "j", inclusive, each of said combinations of letters designating a certain play of a baseball game, whereby certain combinations of letters may be inserted in the blank spaces on said score card for 120 completing a perfect score card.
